Dexter Pierce

UNITED STATES PATENT OFFICE.

D. PIERCE, OF SUNAPEE, NEW HAMPSHIRE.

CLOTHES-PIN.

Specification forming part of Letters Patent No. 20,364, dated May 25, 1858; Reissued August 20, 1872, No. 5,041.

To all whom it may concern:

Be it known that I, DEXTER PIERCE, of Sunapee, in the county of Sullivan and State of New Hampshire, have invented a new

5 Improvement in the Article Commonly Called a "Clothes Clamp or Pin;" and I do hereby declare that the following is a full and exact description thereof, reference being had to the accompanying drawing and

10 to the letters of reference marked thereon.

That others skilled in the mechanic arts may be able to make and use my invention I will endeavor to describe as briefly as I can its form and mode of construction.

15 I am aware that plain turned pins, whether "headed" or otherwise, are open to several objections, among which is prominent the difficulty of making the limb of the pin light enough to be sufficiently yielding,

20 and at the same time retaining the necessary size to afford the requisite strength. The main cause of this difficulty will at once appear when it is suggested that the pressure of the limbs of the pin apart is exceedingly

25 unnatural, from the fact that the back or outside of each limb is in the form of an arc, and is consequently braced against the bend or "spring" required; the plain and well known result being, that the pin—on the

30 least extra pressure upon the line,—splits or parts in the middle: the fiber of the wood in the center of the pin giving way, because the limbs fail to bend as they ought to do, if they were properly constructed. The exten-

35 sion of the limb of my pin is made, with a view to obviate this difficulty, flat like the inside, so that, even an unreasonable amount of pressure upon the clothes line, instead of splitting the pin will simply cause an en-

40 larged distension of the limbs; as may be

readily tested by pressing the model upon the finger of the examiner or any other partially yielding object, when the superior elasticity of this form of pin will be at once apparent.

15 The limbs, as will be seen in the drawing at "A," "A" retain an equality of thickness until near the end of the slit, when it slightly enlarges, to prevent the breaking off of the one limb or the other, as would be the result if the pin were made entirely straight on the outside. And this enlargement of the limbs of my pin, is made available for another beneficial purpose:—to wit, commences in 50 putting on to, and taking off from the line. By placing the thumb and fore finger in the hollows marked "B," "B," it will be seen that the swell at each side of the hollows,—on pulling the pin off or pressing it on—serve to tighten the grasp of the holder, and 55 therefore, to aid perceptibly in fastening or removing the pin. Another advantage arising from the peculiar conformation of my pin is, that when it is picked up for the purpose of being placed upon the line, the 60 slightest touch will at once inform the user whether they have got it in proper position, 65 without the trouble of ocular examination: which is a feature not possessed by any other plain unhinged "clamp" that I know of. 70

What I claim as my invention, and desire to secure by Letters Patent, is—

A new article of manufacture: to wit: a clothes pin, all the parts of which are constructed substantially as within set forth.

DEXTER PIERCE.
